UNITED STATES PATENT OFFICE

90,679

DESIGN FOR A FAUCET

Frank J. Polcer, Cicero, Ill.

Application June 27, 1933. Serial No. 48,560

Term of patent 7 years

To all whom it may concern:

Be it known that I, FRANK J. POLCER, a citizen of the United States, residing at Cicero, in the county of Cook and State of Illinois, have invented a new, original, and ornamental Design for a Faucet, of which the following is a specification, reference being had to the accompanying drawing, in which:—

Fig. 1 is a plan view, and
Fig. 2 is a side elevation of the article showing my new design.

I claim:—
The ornamental design for a faucet, as shown.
In testimony whereof I affix my signature.

FRANK J. POLCER.
